ROTARY LINEN FINISH CALENDER

Hugo H. Hanson, Philadelphia, and George Craven, Conshohocken, Pa., assignors to W. C. Hamilton and Sons, Miquon, Pa., a corporation of Pennsylvania

Application August 20, 1930. Serial No. 476,694

11 Claims. (Cl. 101—23)

This invention relates to linen-finish calenders, and more particularly to a machine for producing linen-finish paper in a continuous web by passing the same through rolls. It has been heretofore impossible to practically produce a commercial grade of linenzied paper approaching in quality the paper produced by the plate process by means of linen covered, or linen cover simulating rolls directly engaging a web of paper passing therebetween. A number of attempts have been made to produce such paper by the use of rolls but the closest approach in a practical structure to the actual use of a roll consists in the use of rolls between which 15 linen webs are passed and between the linen webs of which the paper web is passed. In some instances the linen web is an endless band and in other instances the linen web is a strip which is transferred from one side of the machine to 20 the other. In the latter construction the length of the linen web employed will, of course, determine the length of the web of paper which can be produced in a single operation. In the former construction where an endless band of linen 25 is employed, some means must be provided to hold this band in a position preventing its buckling or cracking, such means materially increasing the bulk of the machine and being otherwise disadvantageous. A machine employing such endless belts, however, very closely approximates the finish produced by the plate process of linenzizing.

While attempts have been made to produce rolls having the linenzizing surfaces directly applied thereto, such attempts have all been failures due to the fact that the rolls were either too hard or too soft. We have discovered that by making these rolls of a proper elastic density the linenzizing surface produced by the plate 40 process can be very closely approximated, if not duplicated, and a continuous web of linenzied paper of high quality produced by passing the same through rolls with which they are in direct contact. Accordingly, an important object of 45 the present invention is the production of a linen-surface roll having the proper density to enable its use in direct contact with the paper being linenzized.

This and other objects we attain by the structure shown in the accompanying drawing wherein, for the purpose of illustration, we have shown a preferred embodiment of our invention and wherein:

Fig. 1 is a side elevation of a linenzizing calen-

der constructed in accordance with our invention;

Fig. 2 is a front elevation thereof;

Fig. 3 is a longitudinal sectional view through 60 one of the calender rolls; and

Fig. 4 is a fragmentary transverse sectional view through the roll.

Referring now more particularly to the drawing, the numeral 10 generally indicates a linenzizing calender machine, and 11 and 12 upper 65 and lower rolls mounted therein for rotation and maintained in pressure contact through a pressure-regulating member generally designated at 13, which may be of any suitable character. Each roll 11 and 12 has a linen cover 14 consisting of from 1 to 5 plies of linen and a core 15 of such character that the elastic density of the roll at its outer surface gives a scleroscope reading on the standard scleroscope of from 45 to 70. The term "elastic density" is employed 70 as defining the density of the roll due to the fact that the actual density thereof is considerably less than the scleroscope test thereof would seem to indicate the increase in the apparent density of the roll being due to the inherent 75 resilience or elasticity thereof. The core 15 of the roll is preferably constructed from a fibrous, or fibrous base material and should have an elastic density in response to scleroscope tests with the standard scleroscope between 35 and 80 50. The best results are obtained by use of a core having an elastic density between 45 and 50, giving in a finished roll a surface density 85 after application of the linen thereto of from 45 to 70. It has been found that the elastic density 90 of the completed roll increases with the number of plies of linen applied thereto and that best results are obtained where the number of plies of linen is such that the surface elastic density lies between 60 and 70.

In construction of the core, a base shaft 16 is preferably employed upon which, between end flanges 17 affixed to the shaft, a series of paper discs 18 is placed. The most efficient paper for use in this connection is manila rope paper and 100 after a sufficient number of discs have been placed in position the core is axially compressed until the required elastic density thereof is obtained. The plies of linen are preferably individually applied and butt jointed as indicated 105 in Fig. 4, each ply being glued in position and thoroughly dried before the next ply is placed in position thereon. Adjacent plies will have the joints thereof staggered as indicated. When the 110 desired number of plies has been applied to the

roll, the surface of the roll is painted with a solution of formaldehyde preferably about a forty percent solution.

Very satisfactory results have been obtained by the use of rolls constructed as described where the elastic density of the core by scleroscope reading was 47, and 5 plies of linen were applied to this core with a resultant final elastic density for the roll of 63 by scleroscope test. It may be noted that the quality of the product increases both with increase of the elastic density of the core and with the increase of the number of plies of linen employed. The elastic density of the roll at its surface increases with the number of plies of linen applied thereto; for example, in the roll hereinbefore mentioned in which the core had an elastic density of 47, the density of the roll with one ply of linen is 50; with two plies, 53; with three plies, 56; with four plies, 60; and with 5 plies, 63. It will be understood that these figures are those for a given roll and that a slight variation might occur in production of a second roll even though the core characteristics were the same, due to the differences in manipulation and in application of the linen plies. Slight variations of this character do not, however, affect the finished product. It is desirable that, in the machine, the rolls 11 and 12 very closely approximate one another in elastic density.

In use of the apparatus, the pressure placed on the rolls is preferably such that adjacent surfaces of the rolls are slightly flattened at the point of contact. With a roll of the hardness described, this flattening occurs at usual linenzizing pressures, which are 40 to 60 tons. The previously moistened paper web to be linenzized is then continuously passed between the rolls, of which one is preferably driven and drives the other by frictional contact therewith through the web W. The linenzizing effect produced by such a machine, as hereinbefore stated, substantially duplicates that produced by the plate process and is of quite as high commercial value as the papers produced by machines employing linen bands passed between adjacent surfaces of the rolls.

As the type of machine in which the rolls are employed is obviously unimportant and as the construction of the rolls themselves is capable of a considerable range of change and modification without departing from the spirit of our invention, we do not wish to be understood as limiting ourselves thereto except as hereinafter claimed.

We claim:

1. A linen covered non-ferrous calender roll for use in producing linenzized paper having an elastic surface density between 45 and 70 by scleroscope test.

2. A calender roll for a linenzizing machine comprising a non-ferrous core having an elastic density between 35 and 50 by scleroscope test and one or more plies of linen covering said core, the roll having a surface density not less than 45.

3. A calender roll for a linenzizing machine comprising a non-ferrous core having an elastic density between 45 and 50 by scleroscope test and

one or more plies of linen covering said core, the roll having a surface density not less than 45 by scleroscope test.

4. A linenzizing calender comprising pressure-engaged linen-surfaced non-ferrous rolls having an elastic density at the surfaces thereof of between 45 and 70 by scleroscope test.

5. A linenzizing machine comprising linen-surfaced non-ferrous calender rolls in forcible engagement with one another, said rolls having a surface density by scleroscope test between 60 and 70.

6. A linenzizing calender comprising pressure-engaged linen-covered rolls, said rolls each comprising a non-ferrous core having an elastic density between 35 and 50 by scleroscope test and one or more plies of linen covering said core, the surface densities of the completed rolls lying between 45 and 70 by scleroscope test.

7. A linenzizing calender comprising pressure-engaged linen-covered rolls, said rolls each comprising a non-ferrous core having an elastic density between 35 and 50 by scleroscope test and one or more plies of linen covering said core, the surface densities of the completed rolls lying between 45 and 70 by scleroscope test, and being substantially identical in the two rolls.

8. A linenzizing calender comprising linen-covered rolls adapted to engage one another through a strip of paper to be linenzized, said rolls each comprising a non-metallic core and one or more plies of linen providing a continuous covering for said core, said rolls being of equal surface densities, a driving means connected to one of said rolls only, and means to urge the rolls into engagement with one another with a pressure sufficient to cause a slight flattening of the rolls at the bite.

9. A linenzizing calender comprising linen-covered rolls, said rolls each comprising a non-metallic core having an elastic density between 35 and 50 by scleroscope test and one or more plies of linen smoothly covering said core, the surface densities of the completed rolls lying between 45 and 70 by scleroscope test, driving means connected to one only of the rolls, and means for urging the rolls together with a pressure sufficient to cause a slight flattening of the rolls at the bite.

10. A calender roll for use in linenzizing machines comprising a non-metallic core having an elastic density between 35 and 50 by scleroscope test, and one or more plies of linen smoothly covering said core, the roll having an elastic density at its surface between 45 and 70 by scleroscope test.

11. A roll for a continuous linenzizing calender comprising a non-metallic core and a continuous linen cover therefor comprising one or more plies of linen, said roll having a hardness such that it forces the threads of linen into the treated paper at linenzizing pressures, resists flattening at pressures below linenzizing pressures and has only a slight flattening at linenzizing pressures.
